DESIGN FOR A GRILLE FOR A LIGHTING FIXTURE

Norman H. Vacha, Cleveland Heights, Ohio

Application October 26, 1940, Serial No. 96,106

Term of patent 3½ years

To all whom it may concern:

Be it known that I, Norman H. Vacha, a citizen of the United States, residing at Cleveland Heights, in the county of Cuyahoga and State of Ohio, have invented a new, original, and ornamental Design for a Grille for a Lighting Fixture, of which the following is a specification, reference being had to the accompanying drawing, forming a part thereof.

In the drawing, the single figure is a perspective view, as seen from below, of a grille for a lighting fixture, showing my new design.

I claim:

The ornamental design for a grille for a lighting fixture, as shown.

NORMAN H. VACHA.
